A. D. T. Libby
ATTORNEY

UNITED STATES PATENT OFFICE.

GEORGE EDMUND GRUNDY, OF ELIZABETH, NEW JERSEY, ASSIGNOR TO THE THOMAS & BETTS CO., OF ELIZABETH, NEW JERSEY, A CORPORATION OF NEW JERSEY.

CLAMPING STRAP.

Application filed June 28, 1926. Serial No. 118,344.

This invention relates to a device in the form of a clamping strap, particularly adapted for use in the electrical trade, for clamping wire conduits, either metallic or non-metallic, armored conductors, or non-metallic cable, etc.

So far as I am aware, it has been the practice in the past to use straps or clamps which have been formed upon a punch press, or other suitable machine, and which clamps are quite rigid in their construction.

Clamps of the kind which I have just described are more or less expensive and bulky, relatively speaking, and not readily carried in a workman's pocket, in quantity.

It is one of the objects of my invention to provide a clamping strap which is much cheaper to make, and one that is lighter and of such a nature that a large number of them can be packed into a box or package, thereby reducing transportation expenses, furthermore a large number of them can be very easily carried by a workman in his pocket, so that he will have straps readily at hand to carry on the work of installing the conduits or cables etc.

Another object of my invention is to provide a clamping strap which is adapted to take different sizes of conduits or cables, thereby making the strap a universal one.

Another object of my invention is to provide a strap which lends itself to quick and easy installation for all sizes of conduit and cable.

A further object is to provide a strap carrying means which act to lock the strap in position on the surface carrying the conduit or cable and at the same time to lock the strap holding means in fixed position.

These and other objects will be apparent to one skilled in this particular art, after a study of the specification taken in connection with the annexed drawing, wherein:

Figure 1, is a plan view of my clamping strap.

Figure 2, is a side view of Figure 1.

Figure 3 shows the strap bent over an armored cable ready to drive the clamp holding means into final position.

Figure 4 is a view similar to Figure 3 showing the clamp embracing a non-metallic covered cable.

Figure 5, is a section on the line 5—5 of Figure 4.

Figure 6, is a view showing how the

clamps are assembled in packages for shipment or handling.

Figure 7, is a view showing a modified form of clamp.

Figure 8 shows one way of utilizing the clamps in practice, whereby a number of the clamps are initially set in position on the surface to which the cable is to be attached, previous to laying the conduit or cable in position, the latter being shown in dotted lines.

Referring now to the details, wherein like numbers refer to corresponding parts in the various views, 1 is a clamp of relatively thin metal, preferably of soft steel, so that the same may be readily bent by the fingers of the operator. In one end of the clamp 1, is a hole 2, and in the other end a series of indentations 3. The hole 2, is adapted to receive clamp securing means 4, which may be a 6d. or other common nail. Preferably the hole 2 is large enough to provide clearance for the nail 4.

As shown in Figure 3, the clamp 1, is bent around a steel armored conduit 5, carrying the usual conductors 6 and 7, insulated in a well-known manner.

In attaching the armored cable 5, to a wood surface such as the framework of a building, the strap 1, is of such a character that it can be quickly bent with the fingers around the cable and the nail 4 is inserted through the hole 2, and then driven through the proper indentations 3, so as to securely grip and clamp the cable 5 to the supporting surface. This is more clearly shown in Figure 5, which shows the nail 4, ready to be driven "home" thereby puncturing the indentations and driving them into the wood surface 8.

It will be apparent that in the act of perforating the indentations 3, by driving the nail 4, through, that the edges of the indentation will act as wedges to grip into the nail 4, to prevent the same from being readily withdrawn or shaken loose. In addition to the indentations 3, I may also use a supplemental indentation 9 as shown in Figures 4 and 5.

In Figure 7, the strap 1, is shown with a depressed portion 10, and the indentations 3 are formed downwardly from the depression 10, thereby giving a modified form of gripping surface for the end of the strap.

Figure 8, shows a plurality of straps 1,

which may be applied to the wood support 8, previous to laying the conduit or conductor in position. This is readily and quickly done by laying the straps against the member 8, and striking the end of the indentations 3 with a hammer, pressing these into the wood so that a number of straps are thus held in place, and the conduit or cable can be then laid in position, and the 10 end having a hole 2, may be then bent over the conduit or cable, and the nail 4 driven "home" as above described.

Figure 6, shows how the straps are assembled for shipment purposes, or for the use 15 of the operator. A bundle of 25 of these occupy an extremely small space and therefore a large number of the straps may be carried in the operator's pocket without any inconvenience; of course, it is obvious 20 that the size of the packages may be varied to suit conditions.

From what has been said, the objects of my invention will be readily appreciated and understood without further description.

25 Having thus described my invention, what I claim is:

1. A device of the class described, comprising a relatively thin metallic strip adapted to be bent by hand over the object 30 to be clamped, one end of said strip having a hole therein and the other end of the strip having a plurality of indentations for engaging the surface to which the object is to be fastened, said indentations adapted to 35 be perforated by a member driven therethrough, said driven member being gripped by the edge of the perforated hole substantially as and for the purpose described.

2. A device of the class described, comprising a relatively thin metallic strip having a plurality of indentations at one end for gripping into a supporting member, said strip adapted to be readily bent by the operator, over an object to be clamped, said 45 indentations being adapted to be selectively perforated by a member driven therethrough and passing through the opposite bent-over-end of the strip, whereby the object is securely held by the bent-over strip.

50 3. Means for clamping an electrical cable, comprising a normally flat metallic strip having an opening in one end and a plurality of indentations at the other end, said strip being readily formed by hand into a loop over the cable, said loop being drawn 55 into engagement with the cable and fastened to a support by a member driven through

said opening in the strip and through one of the selected indentations, substantially as described.

4. Means for clamping an electrical cable, comprising; a normally flat metallic strip having an opening in one end, and a plurality of indentations at the other end, said strip adapted to be temporarily attached to a support member by a blow on the strip over the indentations, said strip being readily bent over the cable after it is put into position over the strip, and a member driven through said opening and a selected one of the indentations into the support.

5. Clamping means for an electrical cable comprising; a flat metallic member adapted to be bent into a loop by hand over the cable and a member passing through both 75 ends of the loop alongside the cable into a support, said member being forcibly driven through the strip and gripped by the metal around the edge of the hole broken through the strip at least at one end of the loop substantially as and for the purpose described.

6. A clamping strap comprising a strip of metal bendable by hand around the object to be clamped having a clearance opening in one end and a plurality of indentations at the other end, said strap being held in position by a member passing through the opening and driven through a selected one of said perforations into a support.

7. As an article of manufacture, a clamping strap for an electrical cable comprising; a flat strip of metal adapted to be stacked into a compact bundle for shipment and handling; each of said strips having a opening in one end and gripping indentations at the other end, each of said strips being readily bendable by hand into a loop over the cable and held in position by a nail driven through the opening and one of said 100 indentations.

8. A universal electrical cable strap comprising; a normally flat strip of metal easily bendable by hand over the cable, said strap having an opening in one end and a plurality of indentations longitudinally spaced from the other end, said indentations being such that a nail positioned in said opening, may be readily driven through a selected indentation depending on the diameter of the cable, into a support to draw the ends 110 of the strap together over the cable.

In testimony whereof, I affix my signature.

GEORGE EDMUND GRUNDY.
